J. SHARP ET AL.
SPARK PLUG.
FILED MAR. 19, 1921.

UNITED STATES PATENT OFFICE.

JOHN SHARP AND WILLIAM SHARP, OF CLEVELAND, OHIO.

SPARK PLUG.

Application filed March 19, 1921. Serial No. 453,647.

To all whom it may concern:

Be it known that we, JOHN SHARP and WILLIAM SHARP, citizens of the United States, and residents of Cleveland, in the 5 county of Cuyahoga and State of Ohio, have invented certain new and useful Improvements in Spark Plugs, of which we hereby declare the following to be a full, clear, and exact description, such as will enable others 10 skilled in the art to which it appertains to make and use the same.

The objects of the invention are to provide an improvement in means for attaching terminals for spark plugs, by means of 15 which a rigid connection is made for the central terminal with the central insulation, and a rigid ground terminal is provided which will not change its form under all working conditions of temperature or 20 rough usage. Also, simple and efficient forms of construction are provided for both terminals, which can easily and conveniently be constructed and assembled.

Further, the invention includes a simple, 25 rigid and serviceable means for attaching the central insulated terminal to the central insulation without screw-threading the connected parts and without expensive machining of any kind while being made.

30 The invention is hereinafter described, shown in the accompanying drawings, and specifically pointed out in the claims.

In the accompanying drawings, Fig. 1 is a side elevation of the device; Fig. 2 is a 35 longitudinal central section of the device; Fig. 3 is a perspective of the connection for the central terminal, shown in Fig. 2; Fig. 4 is a section showing a modified form of connection for this purpose; Fig. 5 is a bottom view showing the connection for the 40 ground terminal; Fig. 6 is a plan of a modified form of ground terminal; Fig. 7 is a perspective of an integral terminal shown in Fig. 5; Fig. 8 is a perspective of a two-piece terminal shown in Fig. 5; Fig. 9 is a plan of a modified form of anchoring 45 skirt for the central terminal, shown in Fig. 4; Fig. 10 is a perspective of the skirt; Fig. 11 is a section showing a screw connection for the parts.

In these views, A is the metal body of the plug; B is the central insulation; C is the packing nut; D is the central insulated terminal; and E is the ground or body 55 terminal.

The central insulated terminal is formed

of a rod of sparking alloyed metal, and its outer end is embedded in the metal head, F, which rests upon the outer end of the insulation, B, and is rigidly secured and anchored thereto, so that the internal pressure upon the rod will not force it out of the insulation, and the action of the binding nut, G, when it is tightened to secure the circuit wire, H, will not loosen it. 60

In Figs. 2 and 3, one form of anchor is shown, and in Figs. 4, 9 and 10, another form is shown.

In Fig. 3, a slotted skirt, I, is shown, attached to the head, H, which may be made 70 of cheaper and dissimilar metal.

This skirt is provided with a shoulder, J, which is retained within the annular groove, K, by means of a heat-resisting and self-hardening cement at L, which flows through 75 the slot, L'.

In Figs. 4, 9, and 10, the skirt, M, is punched from sheet metal and provided with dovetailed extremities, between which the cement will flow, and when hardened will 80 prevent longitudinal or rotary movement of the head.

This skirt is preferably attached to the head by means of a central eyelet, O, which is integrally attached to the head, by turning 85 its edge over the horizontal disc portion, o², of the skirt, which is provided with an opening, o³, through which the eyelet passes.

Also, the inner edge is forced, by means of 90 a punch applied at P, P, over the edge of the disc, o³, thus locking the head and skirt together and preventing the rotation of the head on the skirt.

In Figs. 5, 6, 7, and 8, the ground terminal, E, is shown.

This terminal is provided with a diamond shaped or elongated opening, R, therein, through which the insulated terminal projects. 100

This gives a wide active surface for engaging the discharge of the spark from the central terminal, and the shape insures complete rigidity of the terminal and also provides for the free and complete circulation 105 of gas thereabout, and also its vertical sides present narrow surfaces upon which the oil will not be retained, and is easily cleaned.

The electric contact is also perfect at both ends, S, which are inserted in slotted openings, T, cut in opposite sides of the inner end of the body of the spark plug. 110

This terminal can be constructed in any one of the several ways illustrated. In Fig. 5, it is formed of two bent plates or wires of sparking alloyed metal, having parallel extremities which are inserted face to face in the grooves, T, in the spark plug body, and the edges of the grooves are swaged over these extremities. The construction is shown also in Fig. 8.

10 In Fig. 7, the parts of the terminal are shown integral and are stamped from one piece of metal; in Fig. 4, a flat metal stamping is shown.

The rigidity of this terminal is secured by 15 the diamond or elongated shape thereof; and the adjustability of the parts to control the length of the spark is easily obtained by bending the end of the insulated central terminal, D, towards or away from the narrow extremities of the opening in the ground terminal.

The walls of the opening T, T, present shoulders which prevent the terminal from shifting in either direction.

25 In Fig. 11 a modified form of anchor is shown, where the skirt, I, is secured by cement, as shown in Fig. 2, and a screw, F¹, passing through it, secures the wire clamping nuts, F² and G, in place.

30 The central terminal, D, is embedded in the head of the screw at D'.

Having described the invention what we claim as new and desire to secure by Letters Patent is:

35 1. In a spark plug, the combination with a metal body and central insulation and central terminal secured to said central insulation of a transversely placed ground terminal composed of flat metal sides turned upon 40 edge to present flat surfaces to said central terminal the extremities of said ground terminal embedded throughout their entire

depth in opposite sides of said metal body and the central portions of the flat metal sides of said ground terminal separated to 45 enclose said central terminal between therein.

2. In a spark plug in combination with the metal body central insulation and central terminal a flat metal ground terminal formed in two duplicate portions and having its extremities embedded in opposite sides of said body said portions turned upon 50 their edges and engaging each other at each end and having their central portions separated to enclose said central terminal.

3. In a spark plug, the combination with the metal body and central insulation, of a central terminal, a head provided with an annular skirt said skirt provided with lateral openings, said insulation provided with 60 an annular slot in its outer end, in which said skirt is embedded, and self hardening cement in said slot said cement forming means for locking said skirt and head in said insulation.

4. In a spark plug, the combination with the metal body and central insulation, of a central terminal, a head provided with an annular skirt said skirt provided with lateral openings, said insulation provided with 70 an annular slot in its outer end, in which said skirt is embedded, and a self hardening cement in said slot said cement forming means for locking said skirt and head in said insulation, and means for attaching the 75 skirt to said head.

In testimony whereof, we hereunto set our hands this 1st day of March, 1921.

JOHN SHARP.
WILLIAM SHARP.

In presence of—

W. M. MONROE,
SOL W. WYMAN.
